US0D1060343S

(12) **United States Design Patent** (10) **Patent No.:** **US D1,060,343 S**
(45) **Date of Patent:** **** Feb. 4, 2025**

(54) **WIRELESS NETWORK DEVICE**

(71) Applicant: **Samsung Electronics Co., Ltd.**, Suwon-si (KR)

(72) Inventors: **Hyungjun Koo**, Suwon-si (KR); **Jihee Kwak**, Suwon-si (KR)

(73) Assignee: **SAMSUNG ELECTRONICS CO., LTD.**, Gyeonggi-Do (KR)

(**) Term: **15 Years**

(21) Appl. No.: **29/854,355**

(22) Filed: **Sep. 23, 2022**

(30) **Foreign Application Priority Data**

Jul. 25, 2022 (KR) 30-2022-0029888

(57) **CLAIM**

The ornamental design for a wireless network device, as shown and described.

DESCRIPTION

FIG. 1 is a front perspective view of a wireless network device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective thereof.

In the drawings, the portions of the wireless network device shown darker than the surrounding claimed subject matter within the broken lines form no part of the claimed design.

1 Claim, 5 Drawing Sheets
